(57) **CLAIM**

The ornamental design for a combination cup and dispenser, as shown and described.

DESCRIPTION

FIG. 1 is a left side perspective view of a combination cup and dispenser showing my new design;

FIG. 2 is a left side elevational view thereof;

FIG. 3 is a top plan view thereof;

FIG. 4 is a bottom plan view thereof;

FIG. 5 is a rear elevational view thereof; and,

FIG. 6 is a front elevational view thereof.

The broken lines in the drawing depict portions of the combination cup and dispenser that form no part of the claimed design.
